FLOATING HEAD FOR HEAT EXCHANGERS

Melvin Sack, Louisville, Ky., assignor to Henry Vogt Machine Co., Inc., Louisville, Ky., a corporation of Kentucky

Application February 11, 1939, Serial No. 255,990

3 Claims. (Cl. 257--239)

This invention relates to heat exchanger of the shell-and-tube type, in which a bundle of tubes having their opposite ends fixed in tube sheets are so placed in the shell that while one tube sheet is anchored with respect to the shell, the opposite tube sheet is freely slideable relative to the shell, to permit unrestrained expansion and contraction of the tubes relative to the shell.

The floating tube sheet in this type of heat exchanger carries a cap which forms with the tube sheet a sealed chamber at the end of the tube bundle for receiving the fluid which circulates through the tubes. This cap moves with the floating tube sheet, and the entire assembly at that end of the tube bundle is known as the floating head. In this type of heat exchanger, the tube bundle, including the floating tube sheet, after removal of the cap, is of a diameter sufficiently small to permit the ready removal of the tube bundle as a unit, including the tubes and both tube sheets, from the shell, for purpose of repair and periodic cleaning, upon detachment of the anchored tube sheet from the shell.

In order to effectively seal the connection between the floating tube sheet and the cap of the floating heat, a very tight joint between them must be provided.

In my Patent No. 1,895,735, granted January 31, 1933, of which the present invention is an improvement, I have provided bolts passing through a peripheral series of apertures in the rim of the cap, said bolts having at their inner ends right angularly disposed toes, which in the normal position of said bolts extend beneath the edge of the floating tube sheet, so that when the bolts are tightened the tube sheet is clamped in a sealed manner against a seating rabbet formed within the cap.

It has been found that inasmuch as the clamping pressure is exerted between the tube sheet and a part of the bolt which is to one side of the axis of the bolt, there is a tendency for the toe portion of the bolt to bend backwardly, sometimes resulting in the fracture of the bolt at the angle between the toe and shank, and in any event, reducing the clamping pressure between the bolt and tube sheet and causing the toe of the bolt to bear unevenly against the tube sheet with the greatest pressure at the extreme edge of the tube sheet, sometimes resulting in crushing of the metal of the tube sheet.

One of the objects of the present invention is to provide a construction in which the cap is provided with a downwardly extending flange, which in the normal tight position of the bolts extends

downwardly below the horizontal plane of the angle between the shank and the toe of the bolt. In other words, said flange backs up the bolts, including the toe portions, so as to resist the backward bending tendency of the bolts when under 5 clamping pressure.

Another object of the present invention is to provide the cap with individual recesses for the toe portions of the bolts, into which the bolts drop only when the toe portions are in position 10 to engage the lower face of the tube sheet, this giving an indication to the workman who is tightening or loosening the bolts from the outside of the cap, as to whether the bolts are in position to engage the tube sheet, or whether the toe portions are not in sidewise position with respect to the tube sheet, clearing the latter so that the cap can be removed.

Still another object of the invention is to provide a bolt of increased mass and diameter in the lower shank portion and in the toe portion, that is, in those portions which suffer the bending stress so that they will not bend outwardly, and that the flat and extensive area of contact between the toes of the bolts and the tube sheet 25 will be preserved.

Other objects of the invention will appear as the following description of a preferred and practical embodiment thereof proceeds.

In the drawings throughout the several figures 30 of which the same reference characters have been employed to designate identical parts:

Figure 1 is a longitudinal section through that portion of a heat exchanger of the type described which embraces the floating head;

Figure 2 is a diametrical section taken along the line 2—2 of Figure 1, viewed in the direction of the arrows;

Figure 3 is a perspective view of the cap; and Figure 4 is a perspective view of the bolt.

Referring now in detail to the several figures, 40 the numeral 1 represents in general the shell, having the end flange 2. Within the shell is the tube bundle 3, composed of a plurality of tubes

4. It will be understood that means are provided in that part of the heat exchanger which is not shown, for causing the fluid within the tubes to flow into the floating head from a certain group of the tubes, and then to flow out from the head into another group of the tubes, 45 this system of circulation being conventional in the art. The ends 5 of the tubes 4 are fixed in the floating tube sheet 6. Said tube sheet is small enough in diameter to pass through the shell 1 as a unit with the tube bundle, in order 50

to permit removal of the tube bundle by drawing it out through the end of the heat exchanger which is not shown. The open ends 5 of the tubes communicate with a chamber 7 formed within the cap 8. Said cap has an internal rabbet 9 against which the upper peripheral margin of the tube sheet 6 seats in a fluid tight manner, a gasket 10 intervening. The cap 8 has a rim 11 which extends beyond the rabbet 9 and is formed with a peripheral series of bolt holes 12 formed outside of the circle which represents the diameter of the tube sheet 6. The rim 11 is provided with a flange 13, which extends downwardly to a plane below the plane of the lower surface of the tube sheet 6, when said tube sheet is resting against the rabbet 9. Said bolt holes 12 are open through the front face of the flange 13, as is indicated at 15 in Figures 3 and 4, thus having a non-round cross-section in a plane diametrical with respect to the heat exchanger. The recesses 14 are of such depth that their bottom walls, indicated by the dotted line 16 in Figure 1, extend slightly outwardly with respect to the plane of the inner face of the tube sheet 6. The bolt holes 12, as is shown in Figure 1, are preferably of two diameters, corresponding to the shape of the bolts, which latter are best shown in Figures 1 and 4. Said bolt holes have an outer part of relatively small diameter and an inner part, relatively enlarged. The bolts, which in general are designated by the reference character 21, comprise a threaded shank portion 17 of relatively small diameter, and a lower shank portion 18 of larger diameter, and a toe 19, which is offset at right angles from the shank of the bolt, and being preferably greater in cross-sectional area than the enlarged portion 18 of the shank. The toe 19 is preferably rectangular in cross-section, providing a broad flat face 20 for direct engagement with the lower peripheral margin of the tube sheet.

It will be observed from Figure 1 that when the bolts 21 are in clamped relation to the tube sheet, there is necessarily a slight clearance 22 between the back of the bolt and the flange 13. The massive portion of the shank 18 and of the toe 19, prevents any backward bending of the bolt through any normal sealing pressure between the toe 20 and the tube sheet 6. The large mass of the bolt, particularly back of the angle between the toe and shank portion, prevents any undue strain or fracture of the bolt at the apex of this angle, due to normal clamping pressure. The broad flat face 20, therefore, rests true against an extensive area of the tube sheet, distributing the clamping pressure and preventing crushing of the tube sheet. Should extraordinary pressure be brought upon the bolts through excessive tightening of the nuts 23, so that the bolts do bend back throughout the extent of the small clearance 22, further outward deflection of the bolts is prevented by the flange 13, which not only backs up the enlarged portion of the shank of the bolt, but also the back of the toe 20, which in the position illustrated in Figure 1 is seated within the recess 14.

When a wrench is brought to bear upon the nuts 23 in the act of loosening the bolts 21 for removing the cap 8, there is no chance of the bolt turning with the nut, for the position of the toe 20 in the correspondingly shaped recess 14 absolutely prevents rotation of the shank of

the bolt, so that the nut must loosen. When the nut has been backed off on the shank a sufficient distance to cause the toe to be pushed out of recess 14, the shank of the bolt can then be rotated so as to cause the toe to move out of the way of the tube sheet 6. When the bolts are in this position, the cap can be removed endwise from the tube sheet. In replacing the cap 8, after it has been positioned with the tube sheet resting against the rabbet 9, the workman can pull outward against the shank of the bolt at the same time rotating the bolt until the toe falls into the recess. He then knows that the toe is projecting beneath the tube sheet, and the bolt is in position to be tightened. The nut may then be drawn up to the desired degree of tightness without any chance that the shank of the bolt will turn and throw the toe of the bolt out of operative position.

A cover 24 bolts upon the flange 2 of the shell, 20 and is removed in order to give access to the cap 8 for removing the latter.

While I have in the above description disclosed what I believe to be a preferred and practical embodiment of the invention, it will be understood to those skilled in the art that the specific details of construction as shown and described, are to be regarded as illustrative and not as restricting the scope of the invention as defined in the appended claims.

What I claim is:

1. A floating head for shell-and-tube type heat exchangers comprising a tube sheet having a tube bundle fixed thereto, extending from its inner face and opening in its outer face, a cap closed at one end and having an interior annular shoulder in an intermediate depth plane forming a seat engaging the margin of the outer face of said tube sheet, a chamber being thus defined between the closed end portion of said cap and said tube sheet, with which chamber the tubes of said tube bundle communicate, said cap having a peripheral flange closely surrounding the peripheral edge of said tube sheet and of greater depth than the thickness of said edge, an annular series of bolt holes through said flange close to the inner surface thereof and axially perpendicular to the plane of said seat, the ends of said bolt holes which open in the free end of said flange being expanded to form recesses opening in the inner face of said flange, toe bolts having their shanks in said bolt holes and having angular portions in said recesses adapted to contact the margin of the inner face of said tube sheet, the walls of said bolt holes intersecting the plane in which said angular portions contact said margin, and seating close against said bolts on that side radially remote from said tube sheet to afford support to said bolts back of the angle between said shanks and said angular portions, relative to said shanks under the clamping pressure of said bolts against said tube sheets.

2. A floating head for shell-and-tube type heat exchangers comprising a tube sheet having a tube bundle fixed thereto, extending from its inner face and opening in its outer face, a cap closed at one end and having an interior annular shoulder in an intermediate depth plane forming a seat engaging the margin of the outer face of said tube sheet, a chamber being thus defined between the closed end portion of said cap and said tube sheet, with which chamber the tubes of said tube bundle communicate, said cap having a peripheral flange closely surrounding the

5 peripheral edge of said tube sheet and of greater depth than the thickness of said edge, an annular series of bolt holes through said flange close to the inner surface thereof and axially perpendicular to the plane of said seat, the ends of said bolt holes which open in the free end of said flange being expanded to form recesses opening in the inner face of said flange, toe bolts having their shanks in said bolt holes and having angular 10 portions nonrotatably received in said recesses adapted to contact the margin of the inner face of said tube sheet, the walls of said bolt holes intersecting the plane in which said angular portions contact said margin, and seating close 15 against said bolts on that side radially remote from said tube sheet, to afford support to said bolts back of the angle between said shanks and said angular portions, to resist outward bending of said angular portions relative to said shanks 20 under the clamping pressure of said bolts against said tube sheet.

3. A floating head for shell-and-tube type heat exchangers comprising a tube sheet having a tube bundle fixed thereto, extending from its inner face and opening in its outer face, a cap closed at one end and having an interior annular shoulder in an intermediate depth plane forming a seat engaging the margin of the outer face of

said tube sheet, a chamber being thus defined between the closed end portion of said cap and said tube sheet, with which chamber the tubes of said tube bundle communicate, said cap having a peripheral flange closely surrounding the 5 peripheral edge of said tube sheet and of greater depth than the thickness of said edge, an annular series of bolt holes through said flange close to the inner surface thereof and axially perpendicular to the plane of said seat, the ends of 10 said bolt holes which open in the free end of said flange being expanded to form recesses opening in the inner face of said flange, toe bolts having their shanks in said bolt holes with threaded ends extending outwardly from the closed end of 15 said cap, and having angular portions in said recesses adapted to contact the margin of the inner face of said tube sheet, the walls of said bolt holes intersecting the plane in which said angular portions contact said margin, and seating 20 close against said bolts on that side radially remote from said tube sheet to afford support to said bolts back of the angle between said shanks and said angular portions, to resist outward bending of said angular portions, relative to said 25 shanks under the clamping pressure of said bolts against said tube sheets.

MELVIN SACK.
